LOCOMOTIVE BOILER

Filed May 16, 1928

UNITED STATES PATENT OFFICE

EDWARD J. REARDON, OF CHICAGO, ILLINOIS, ASSIGNOR TO LOCOMOTIVE FIREBOX COMPANY, OF CHICAGO, ILLINOIS, A CORPORATION OF DELAWARE

LOCOMOTIVE BOILER

Application filed May 16, 1923. Serial No. 278,061.

This invention relates to improvements in locomotive boilers and it consists of the matters hereinafter described and more particularly pointed out in the appended claims.

5 The primary object of the invention is to provide in a locomotive boiler embodying the well known Nicholson thermic siphon in the firebox thereof, a new and novel connection for the inlet or neck end of the siphon with the front end corner of one of the side water legs whereby not only a forward circulation of the water therein is produced in said legs but a lateral water circulation is established in the front water leg thus increasing the 10 water movement and steaming characteristics of the boiler and eliminating the formation of the usual still water areas at these points.

Another object of the invention is to so 20 form the neck of the siphon in a gradually sweeping curve that it may be readily attached to the side sheet so that the water circulating through the same will keep it clean and will present a greater surface area to the 25 products of combustion in the firebox, thus increasing the efficiency of the boiler as a whole.

These objects of the invention as well as others together with the many advantages 30 thereof will more fully appear as I proceed with my specification.

In the drawings:—

Fig. 1 is a vertical longitudinal sectional view through the firebox end of a locomotive 35 boiler embodying my invention.

Fig. 2 is a transverse vertical sectional view through the same on the line 2—2 of Fig. 1.

Fig. 3 is a fragmentary detail view partly 40 in elevation and partly in section of a slightly modified form of the invention which will be more fully described later.

Referring now in detail to that embodiment of the invention illustrated in Figs. 1 and 2 of the accompanying drawings:—The 45 locomotive boiler firebox shown therein comprises a fire chamber which extends from the back sheet 1 to the flue sheet 2 and from one to the other of the side sheets 3 with a grate or bottom indicated by the dotted line 4 in Fig. 1. Said grate, as shown herein, extends

from the back sheet 1 to an inner throat sheet 5 which is preferably integral with the flue sheet. The top of the firebox is formed by a crown sheet 6 which extends from the back sheet 1 to the flue sheet 2.

55 In the rear sheet 1 is provided the usual fuel door opening 7 and to the front or flue sheet are connected the usual flues 8 through which the products of combustion are drawn by the exhaust nozzle (not shown) in the manner well known. The firebox is enclosed by a top plate 9 and the usual side plates 10 together with the outside throat plate 11 and back plate 12 which provides what is commonly termed the "wrapper" of the boiler. 60 Such plates together with the sheets of the firebox define the side water legs 13 and front and rear water legs 14 and 15 of the boiler, all of which are closed at their bottom ends by the mud ring 16. The inner sheets defining the firebox and the outer or wrapper sheets are joined or stayed together by the usual stay bolts 17.

70 Within the firebox is located one or more substantially hollow elements 18 which in this instance conduct water from the forward bottom ends of the side water legs of the boiler to the space 19 above the crown sheet. The number of such elements employed, which are known as the Nicholson thermic siphon, is of course dependent upon the size of the firebox and in this instance two of such elements are shown, one on each side of the longitudinal median plane of the firebox.

75 Each water circulating element or body 80 comprises a substantially triangularly shaped flat hollow body 20 with an upwardly and rearwardly inclined bulged bottom 21. The sides of said body are staybolted together and form at the top thereof a longitudinally, elongated discharge opening that is defined 85 by an outwardly extending flange 22 fixed in an opening in the crown sheet for that purpose. The bottom bulged portion extends forwardly and downwardly beyond the body 90 in the form of a tube 23 which is bent downwardly and laterally in curves of generous radii to provide an inlet neck for the siphon. This neck opens through and is fixed in that corner of the adjacent associated side sheet 95 100

near the mud ring and front sheet respectively. Preferably that portion of the side sheet in which said neck is fixed is made in the form of a flexible diaphragm ^{3a} but this feature is not absolutely essential to the broader aspects of the invention.

The water circulating element and its neck is usually made from a single sheet of metal and the welded seam is at the front end there-
10 of and extends down along the neck and to strengthen the neck against interior pressures stay-bolts ²⁴ are employed and these stay-
15 bolts extend at a right angle to the plane of the seam which seam is on the top side of the neck where it enters the side sheet.

In Fig. 3 I have shown a slightly modified form of neck construction which is as follows:—Instead of making the curved neck part as an integral part of the siphon, I may make it from a single piece ²⁵ of seamless tubing and butt weld it at one end as indicated at ²⁶ to the neck extension ^{23a} as shown in said Fig. 3. This construction is advantageous in that it eliminates the use
20 of stay-bolts therein and permits a free and uninterrupted sweep of the water through the neck. Again the neck is that part of the element which receives the heaviest bombardment of the products of combustion and
25 hence receives the greatest amount of mechanical wear. With the seamless neck as shown in Fig. 3, the same may be more easily replaced when worn to that degree wherein safety demands its renewal.

30 In operation, water is drawn from the lower forward end portion of each side water leg, thus causing a sweeping of the water from the rear part forward and also a lateral circulation in the front water leg and throat.
35 This water passes into the neck with a sweeping action, keeping the neck clear and free from sediment and is then discharged out through the top end of the element into the water space above the crown sheet. Thus
40 there is created a flow of the colder water at the bottom of the water legs and boiler spaces so that such water is more thoroughly mixed with the hotter water of the boiler whereby steaming efficiency is increased and
45 unequal boiler strains due to temperature differences are eliminated.

While in describing my invention, I have referred in detail to the form and arrangement of the various parts thereof, the same
50 is to be considered as by way of illustration only so that I do not wish to be limited thereto except as may be pointed out in the appended claims.

I claim as my invention:—

60 1. A locomotive boiler embodying therein a firebox including side sheets, a crown sheet and front and rear sheets, a substantially rigid water circulating element disposed in the firebox and having an elongated discharge end that opens through the crown
65

sheet and has a tubular inlet neck portion that curves downwardly and laterally to open through one of said side sheets at one of the corners of the firebox near the bottom thereof.

70

2. A locomotive boiler embodying therein a firebox including side sheets, a crown sheet and front and rear sheets, a substantially rigid water circulating element disposed in the firebox and having an elongated discharge end that opens through the crown sheet and has a tubular inlet neck portion that curves downwardly and laterally and opens through the adjacent side sheet at the front bottom corner thereof.

75

3. In combination with a thermic siphon having a substantially triangularly shaped flat body portion with a bulged bottom extending beyond one end of said body to form a tubular neck portion and a downwardly and laterally curved seamless neck member secured to said tubular neck portion.

80

In testimony whereof, I have hereunto set my hand, this 10th day of May, 1928.

EDWARD J. REARDON.
